UNITED STATES PATENT OFFICE.

LEWIS A. HAINES, OF HARRISBURG, PENNSYLVANIA.

GOVERNOR FOR STEAM-ENGINES.

SPECIFICATION forming part of Letters Patent No. 369,241, dated August 30, 1887.

Application filed March 30, 1887. Serial No. 232,997. (No model.)

To all whom it may concern:

Be it known that I, LEWIS A. HAINES, a citizen of the United States, residing at Harrisburg, in the county of Dauphin and State of Pennsylvania, have invented certain new and useful Improvements in Governors for Steam-Engines; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

Figure 1 of the drawings is a representation of my invention, and is a front view of the same. Fig. 2 is a front view. Fig. 3 is a detail view. Fig. 4 is a detail view. Fig. 5 is a vertical section. Figs. 6 and 7 are side views.

The invention relates to improvements in that class of automatic governors for steam-engines in which the eccentric has its position shifted by the centrifugal force of a weight or weights to vary the cut-off, the object being to maintain a constant lead at whatever point the cut-off may occur; and it consists in the construction and novel arrangements as herein set forth.

Referring by letter to the drawings, A designates the main or crank shaft, having the hub *b* of a fly or governor wheel, B, secured upon it.

C is a shifting eccentric provided with the boss *c*, forming the seat of the eccentric-strap, and provided with the opening *c'*, through which the shaft A passes and which is longitudinally extended, as shown, to allow the eccentric free movement in relation to the shaft.

c' is a cylindrical guide-sleeve fitting upon the shaft with its inner end abutting against the hub of the governor-wheel. The said sleeve fits in the opening *c'* and guides the eccentric, and has a circumferential flange on its outer end to retain the eccentric in place. The outer end of the sleeve abuts against the pillow-block of the engine.

D D' are similar arms, respectively secured to the ends of the eccentric-plate upon which the cylindrical boss is formed. Each of said ends is provided with the inwardly-standing flange *d*, which forms within it the recess *d'*, the flange having a height equal to the thick-

ness of the corresponding arm, so that the latter when in place will be flush with the inner surface of the eccentric. The recess is of proper size to have the end of the arm fitted snugly therein, and when in place the arm is secured within the recess. The outer ends of the arms are provided with bosses or heads, the centers of which are equally distant from the center point, *x*, of the eccentric. The head E of the arm D is pivoted at *e* to one end of a link, F, the other end of which is pivoted at *f* upon a boss made on the fly-wheel a suitable distance from the center thereof. The head E' of the arm D' is pivoted at *e'* to the end of the arm *f'* of the lever F', which lever is pivoted at *f'* on a boss on the fly-wheel diametrically opposite the boss *f*. The opposite arm of the lever F' has upon it the sliding weight G, rendered adjustable by means of the set-screw *g*.

H is a strong coiled spring having its outer end connected to the end of the lever F' by means of the swinging link *h* and the inner end hooked into the eye of the eyebolt I, which passes through an opening in the head of the swivel-bolt *i*, pivoted through a boss on the wheel B, and which is engaged by a nut on the opposite side of said head for the purpose of adjusting the tension of the spring in the usual well-known manner. The swivel-bolt has a retaining-head on the inner side of the fly-wheel.

The distance between the pivotal points *e* and *f* of the link F is equal to that between the pivotal points *e'* and *f'* of the lever F'. The link and the lever make equal but opposite angles with the arms D D', and the pivoted points of said arms are equally distant from the central point, *x*, of the eccentric; hence, whether the said point *x* be moved nearer to or farther from the center of the crank-shaft, the lap and lead line will remain unchanged in position, and the lead will be kept the same at all points of cut off.

When the load of the engine is decreased, the crank-shaft and fly-wheel will have their rotation increased in speed, and the centrifugal force of the weight will throw the lever F' outward and will move the center, *x*, of the eccentric nearer to the center of the shaft, so that the travel of the valve will be lessened, the cut-off will occur quicker, and less steam

will be admitted into the cylinder; but as the pivotal points *e* and *f* are the same distance apart as the pivotal points *e'* and *f'*, and the arms *D D'* are of equal length, the lap and lead line will not change its position and the lead will remain constant at all points of cut off.

When the load is increased, the motion of the fly-wheel will be lessened, the lever *F'* will move upward by the spring, the center of the eccentric will be moved away from the center of the shaft, and the travel of the valve increased so as to permit the steam to follow the piston farther in the stroke and cause a later cut off.

15 The swivel-bolt turns and permits the spring to move outward without buckling, and the weight of the spring adds to the centrifugal force of the sliding weight.

The above-described construction is more particularly adapted for light engines. For heavy engines it is desirable to use two springs, and to accomplish this the construction is modified as follows: The link *F*, Fig. 2, has its direction reversed and is extended beyond 25 the pivotal point *f*, forming an arm, *J*, having its end connected with a spring, *H'*, by means of a swinging link, *h'*, the other end of the spring being connected to an eyebolt, *I'*, engaging a swivel-bolt, *i'*, which parts are in all respects similar to those formerly described. *G'* is a weight on the arm *J*, similar to the weight *G*. The arm *f''* of the lever *F'* is provided with a slot, *f''*, and a link, *f''*, similar to the link *F*, is pivoted at one end to a boss, *j*, 35 on the fly-wheel opposite the boss *f*. The other end of the link *f''* is pivoted to the arm *D'* and is bifurcated, an anti-friction roller being pivoted between the arms of the bifurcation. The said roller fits and moves in the slot *f''*, so as 40 to give the joint formed by the lever, link, and arm proper freedom of motion.

The operation of this modification is identical with that of the construction first described.

45 When the two springs are used, the weights counterbalance each other and the eccentric is held between them; but when the single spring is used the weight *G* counterbalances the weight of the eccentric over the pivot *f'*, 50 the weight and eccentric being connected to opposite arms of said lever. The parts are so arranged in relation to each other that when the eccentric is at the point of its greatest travel, moving most rapidly, the link *F* and lever *F'* are nearly at right angles to the arms *D D'*, to which they are connected, so that the increased thrust on the eccentric falls upon 55 said link and lever and prevents the springs from being put in unequal tension, so that the 60 motion of the connected parts are equalized and steadied.

Having described my invention, I claim—

1. In a centrifugal governor, the combination of the governor-wheel, the shifting eccentric provided with opposite non-weighted arms, one arm being connected to the wheel

by a link and the other connected thereto by a lever, and mechanism, substantially as described, whereby the eccentric may have its center moved nearer to or farther from the center of the crank-shaft and still keep the lead the same, substantially as specified.

2. In a centrifugal governor, the combination of the governor-wheel, the shifting eccentric having similar opposite arms, *D D'*, a link connecting the end of one arm to the wheel, a lever connecting the end of the opposite arm to the fly-wheel, and a weight on said lever by the centrifugal force of which the center of the eccentric is moved inward toward the center of the crank-shaft, so as to quicken the cut-off without changing the lead, substantially as specified.

3. In a centrifugal governor, the combination of the governor-wheel, the shifting eccentric having opposite arms, the link connecting the end of one arm to the wheel, the lever connecting the end of the opposite arm to the wheel, the pivotal points of the arms being equally distant from the center of the eccentric and also equally distant from the pivotal points of the link and lever on the wheel, the springs, and the adjustable weight on the lever by the centrifugal force of which the cut-off is quickened but the lead not changed, substantially as specified.

4. In a centrifugal governor, the combination of the wheel, the shifting eccentric provided with opposite arms having the pivotal points at their outer ends at equal distances from the center of the eccentric, the link pivoted to the wheel and to the end of one of the eccentric arms, the lever pivoted to the wheel and provided with a slot in which an anti-friction roller on the end of the link moves, 100 the lever pivoted to the opposite arm of the eccentric and to the wheel at a point diametrically opposite the pivotal point thereon of the link and having the distance of its pivotal points on the wheel and arm equal to that of the corresponding pivotal points of the link, the adjustable weights on the levers, and the coiled springs connecting the ends of the levers to the wheel, substantially as specified.

5. In a centrifugal governor, the combination, with the shifting eccentric provided with opposite arms, of the lever and link pivoted to corresponding arms of the eccentric and to the governor-wheel at such points that they will be at right angles to said arms when the eccentric is at its point of greatest travel, whereby the springs are prevented from being put under unequal tension by the increased thrust, substantially as specified.

In testimony whereof I affix my signature in presence of two witnesses.

LEWIS A. HAINES.
